DESIGN FOR A JAR

Frank O. Green, Cleveland, Ohio, assignor to Standard Brands Incorporated, New York,
N. Y., a corporation of Delaware

Application November 2, 1934, Serial No. 53,852

Term of patent 7 years

To all whom it may concern:

Be it known that I, Frank O. Green, a citizen of the United States, and residing at Cleveland, in the county of Cuyahoga and State of Ohio,
have invented a new, original, and ornamental Design for a Jar, of which the following is a specification, reference being had to the accompanying drawing, forming a part thereof.

In the accompanying drawing:

Fig. 1 is a perspective view of a jar showing my design.

Fig. 2 is a side elevational view thereof.
Fig. 3 is an end elevational view thereof.
Fig. 4 is a top plan view.

I claim:

The ornamental design for a jar, substantially as shown.

Signed at Cleveland, in the county of Cuyahoga, and State of Ohio, this 26th day of October, 1934.
